UNITED STATES PATENT OFFICE.

OSCAR C. RIXSON, OF NEW ROCHELLE, NEW YORK.

DOOR-LOCK.

1,316,329.

Specification of Letters Patent. Patented Sept. 16, 1919.

Application filed April 16, 1919. Serial No. 290,511.

To all whom it may concern:

Be it known that I, OSCAR C. RIXSON, a citizen of the United States, residing at New Rochelle, in the county of Westchester and State of New York, have invented certain new and useful Improvements in Door-Locks, of which the following is a full, clear, and exact description.

This invention relates to door locks and pertains more particularly to the kind of lock that is used on "intercommunicating" doors, such doors, for instance, as are located between adjacent rooms in a hotel or office building where it becomes desirable for a party in either room to lock the intervening door against the other. Such locks are usually provided with a spring latch which can be operated from either side by the usual knobs and with two bolts which can be operated from each side, respectively, by means of rotating handles or thumb pieces. The handles enable the occupants of each room to throw the respective bolts to locking and unlocking position, and since one bolt is sufficient to lock the door, both bolts must be in their withdrawn position to unlock the door. In order to prevent the thrusting back of these bolts by means of an instrument passed between the edge of the door and the door frame, a dead-locking device has been provided to be operated by a suitable key mechanism associated with the lock and which is actuated by the superintendent or other officer of the building who may be in possession of the key. This prevents the opening of the door through connivance of the occupants of the two rooms. A feature of my present invention consists in the provision of a deadlocking device which not only operates upon the two bolts mentioned, but also upon the spring latch which is ordinarily under control of the knobs, the latch bolt then becoming a locking bolt which increases the security of the lock as a whole. A further advantage in dead-locking the latch bolt against any movement of the knobs is in the satisfaction which it gives the occupant of the room who learns at once upon trying the knob and finding it immovable, that the door is securely locked. It is also a feature of my invention to provide a key mechanism in association with the lock for actuating the deadlocking device described, which key mechanism is accessible or operable from either side of the door. In other words, I incorporate with the mortise lock a pin tumbler lock having a key passage extending entirely through it and provided with a key so designed with respect to the pin tumblers that the key can be inserted in either direction or from either side of the door to operate the lock. My invention also comprehends certain other details, all of which will be fully set forth in the following specification and claims.

In the accompanying drawings:

Figure 1 shows an interior view in elevation of the complete lock, the lock casing being shown in vertical section;

Fig. 2 is a section through the lock and a portion of the door in which it is inserted, the section being along an irregular horizontal line;

Fig. 3 is a side elevation partially in section of the pin tumbler lock;

Fig. 4 is a plan of the same, with the roll-back omitted;

Fig. 5 shows face and edge views of the roll-back;

Fig. 6 is a detail of spring detent for the bolts;

Fig. 7 is a section on line α — α of Fig. 1; and

Fig. 8 is a plan of one pattern of key that may be used in the pin tumbler lock.

The lock casing is indicated by 1, its face plate by 2, and the cap or cover by 3. The latter is held in engagement with the casing by two screws which are threaded respectively into the post 4 and lug 5 carried by the casing. 6 represents the ordinary spring latch bolt normally held outward by a spring 7 surrounding a tail piece 8 attached to the head of the bolt, but which is adapted to be forced inward by contact with the strike plate when the door closes, or pulled inward in opening the door by means of the roll-back 9 which is operated by the usual knobs and which impinges against a slide 10, which in turn pushes a cross head 11 carried by the tail rod, rearward, the slide being returned to its normal position by a spring 12. In the upper part of the casing are shown two bolts 13 and 14 which work through a single opening in the face plate. These bolts have offset tail pieces 15 and 16 which at their rear ends are parallel and counterparts of each other in shape. The tail piece 15 is provided with

an upstanding lug 17 and directly opposite this lug the tail piece 16 has a similar upstanding lug 18. At the rear end of tail piece 15 it is provided with a shouldered 5 notch 19 which is directly in line with a similar notch at the extremity of the tail piece 16. In each of these notches an independently controlled roll-back is adapted to play in order to project and withdraw 10 the respective bolts. One of these roll-backs 20 only, is shown, its hubs 21 being supposed to be connected with a rotating handle or thumb piece exposed on one escutcheon of the lock, while the handle for the 15 other is exposed on the escutcheon on the opposite side of the door. On an upward projection at the end of each tail piece are formed two arcuate seats 22 and 23, corresponding seats on each tail piece being in 20 line with each other so that a short roller 24 bridging cross the two tail pieces will rest against and in the corresponding curved seats therein. This roller is held against the two seats by a single spring 25 and is 25 prevented from being forced out of operative position by two guards or lugs 26 and 27 attached to the casing. When the roller engages the tail pieces in the position shown in Fig. 1, both bolts are held in their withdrawn 30 position, but by applying force to either bolt through its corresponding roll-back 20, the roller will be thrust or rolled outward slightly against the spring to allow the bolt to move forward and when the next seat 23 of the particular bolt in motion 35 is presented to the roller, the latter will engage with that seat and detain the particular bolt in its projected position while at the same time retaining the stationary 40 bolt in its withdrawn position. It will therefore be seen that this detent device is effective in connection with both bolts regardless of the particular relative position they may be occupying at any time.

45 The forward portions of the two tail pieces 15 and 16 are separated or off-set from each other, as indicated in Fig. 7, to accommodate a deadlocking pawl 28 between them. This pawl is provided at its upper end, which rises above the lugs 17 and 18, with a cross-head 29, which, upon the lowering of the pawl will stand in front of or behind the lugs 17 and 18 preventing the bolts 13 and 14 from moving outward or 55 inward as the case may be. The lower end of the pawl is curved and reaches to a position immediately above and slightly behind the head of the latch bolt 6 and is there provided with a head 30 which is guided vertically 60 between lugs 31 and 32 attached to the casing. The upper end of the pawl is likewise guided between a flat face on the lug 5 and the lug 33, under which guides the pawl is permitted to move vertically. 65 34 is a bell crank pivoted to the casing at 35 and provided with a fork 36 which engages a pin 37 on the rear face of the pawl. When this bell crank is rocked, it will be seen that the pawl is caused to rise or fall, and to retain the pawl in either its upper or 70 lower position the bell crank is provided with a finger 38 which is held in either of two positions by a hump on a spring blade 39, the limit of movement of the bell crank being determined in one direction by a stop pin 40 and in the other by the limited movement of the pawl. The lug 5 serves the additional functions of guiding the two bolts 13 and 14 and also as a stop for the roll-backs 20 when in the opposite position to 80 that illustrated. The bell crank 34 is also provided with a forked arm 41, the members of which are adapted to be alternately struck by a roll-back operated by the key mechanism which will now be described. 85 42 represents the frame of a pin tumbler lock, said frame being cylindrical and having an upward extension 43 in which a series of pin tumblers 44 are housed. Within the frame is located a rotatable 90 plug 45 having a key passage 46 extending entirely therethrough and adapted to receive a key from either end. The pin tumblers are, as usual, arranged in the same plane, which plane also includes the 95 key passage 46, and they are parallel to each other. Each pin tumbler consists, as usual of two or more bolts or pins urged downward by a spring, the function of the key being to so adjust each set of pins that a 100 joint between them will coincide with the joint between the plug and the casing, thereby permitting the plug to rotate. 47 is a roll-back or cam carried by the plug 45 and consisting of a collar having a finger 105 projecting therefrom as shown in Fig. 5, the cam being fixed to the plug by means of a pin 48. The purpose of rotating the plug is to throw this roll-back around to engage and operate the mechanism of the main 110 lock. This key mechanism is made of a length over all corresponding substantially to the thickness of the mortise lock and the mortise lock is provided with two openings 49, 50 in the casing 1 and cover 3, respectively, and directly opposite each other in which the pin tumbler is seated, the extremities of the latter lock occupying the said opening and presenting the open key 115 passage 46 on each face of the mortise lock. 120 The pin tumbler lock when mounted in this way may be made a permanent part of the mortise lock and is therefore removable with the mortise lock from the mortise in the door, which differentiates from the usual 125 type of pin tumbler lock which projects from the mortise lock through the structure of the door and must be removed from the mortise lock before the latter can be removed from the mortise. In conjunction with a pin 130

tumbler lock associated with a mortise lock in this way, I propose to use escutcheons 51 and 52 on the opposite faces of the door, each of which is provided with a rotary member 53 containing a key passage lined up with the key passage 46 of the lock, the members 53 being connected in this position with the rotary plug 45 by means of pins or screws 54 passing from the members 53 into the holes 55 (Fig. 1) of the plug. With the key mechanism inserted in this manner within the mortise lock, the rotation of the plug 45 by means of a key will cause the roll-back 47 to swing in the path indicated by the circular dotted line in Fig. 1, which will cause the roll-back to strike one or the other members of the fork 41 on the bell crank 34 and thus move the pawl up or down. From this it will be seen that the superintendent or other officer of the building, who would ordinarily be in possession of the key to operate this lock, will be able to throw the bolts 13 and 14, one or both, outward by means of the handles connected thereto and then with the key he can lock the bell crank 34 and throw the pawl 28 downward, bringing its head 30 behind the head of the latch bolt 6 and its cross head 29 behind the lugs 17 and 18, one or both, to deadlock the said bolts in their projected position, which condition neither of the occupants of the two rooms will be able to disturb, and both of said occupants will be keenly apprised of the fact that the door is locked because of the failure of the knob to turn. It is desirable to be able to manipulate the key mechanism from either side of the door because in case only one of the communicating rooms is occupied, the key can be used in the other room and thus avoid disturbing the guest in the occupied room. For other obvious reasons, also, it is desirable to be able to manipulate the lock from either side of the door, and this desideratum is afforded by the pin tumbler and lock and key constructed in the peculiar manner hereinafter described.

In order to operate a pin tumbler lock in which the tumblers are arranged parallel to each other and the same plane, from either side of the door, it is necessary to cut two sets of groups of notches on the edge of the key and arrange the tumblers in such a manner that one or both groups of notches in the key will properly set the tumblers regardless of which side of the door the key is entered. The lock as constructed by me is of the size which usually carries five tumblers, but I have omitted one of the intermediate tumblers to provide a place for the roll-back 47, which therefore occupies a transverse plane intersecting the series of tumblers. With the roll-back thus located the ends of the lock, which occupy the openings 49 and 50 in the casing of the mortise

lock can each be utilized to accommodate a tumbler and I am thereby able to use a sufficient number of tumblers to obtain the required security. With the arrangement of tumblers shown, and the accompanying design of key shown in Fig. 8, it will be seen that if the key is inserted from the right-hand side of the lock (Fig. 3), the notches *a*, *b* and *c* of the key will set the first three tumblers while the notch *a'* will set the last tumbler, the notch *b'* of the key not being utilized, and the plug 45 can then be rotated. On the other hand, if the key is inserted from the left hand side of the lock, the notch *a* will set the first tumbler to the left and the notches *c*, *b'*, and *a'* will set the other three tumblers, thus also enabling the plug to be rotated. Obviously the tumblers can be differently disposed along the key passage. There can, for instance, be two on each side of the center, or there may be two or three on one side of the center and none at all on the other. In the latter case, the key would still have two groups of notches, one group near the handle to come into use when the key is inserted at that end of the passage adjacent to which the tumblers are located, and the other at the extremity of the key to engage the same set of tumblers which the key must then reach when inserted from the opposite side. My invention therefore extends to any design of bitting along one edge of a key and any arrangement of tumblers in a row and parallel to each other which will coöperate with said bitting when the key is inserted at either end of the key passage, to release the key plug.

I claim:

1. A lock having a single series of pin tumblers arranged parallel to each other and in the same plane, and a rotary plug having a key passage extending entirely therethrough, in combination with a key having a single line of bitting adapted to coöperate with the tumblers to operate the lock when the key enters either end of the passage.
2. A lock having a series of pin tumblers arranged parallel to each other and in the same plane, a rotary plug having a key passage extending entirely therethrough, and a roll-back carried by the plug and arranged in a plane intersecting the series of pin tumblers, in combination with a key adapted to enter either end of the passage and coöperate with the tumblers to operate the lock.
3. A lock having a series of pin tumblers arranged parallel to each other and in the same plane and a rotary plug having a key passage extending entirely therethrough, in combination with a key having a series of notches on one edge which are arranged in two groups each group being adapted to coöperate with two different groups of the

series of tumblers depending upon the direction in which the key is inserted in the passage.

4. A lock having a plurality of pin tumblers arranged parallel to each other and in the same plane and a rotary plug having a key passage extending entirely therethrough, in combination with a key having a series of notches on one edge arranged in 10 two groups, one group being adapted to co-operate with the tumblers when the key is inserted at one end of the passage and the other group adapted to co-operate with the tumblers when the key is inserted at the opposite end of the passage.

5. In a door lock, the combination of a spring latch bolt and two handle-operated bolts adapted to be thrown from opposite sides of the door respectively with a dead 20 locking pawl adapted to simultaneously engage the latch bolt and either or both of the handle bolts.

6. In a door lock, the combination of a spring latch bolt and two handle-operated 25 bolts adapted to be thrown from opposite

sides of the door respectively with a dead locking pawl adapted to simultaneously engage the latch bolt and either or both of the handle bolts, and a key mechanism for actuating said pawl.

7. In a door lock, the combination of a spring latch bolt, a handle operated bolt and a dead locking pawl adapted to engage both of said bolts, with a key mechanism for actuating the dead-locking pawl.

8. In a lock, the combination of a pair of bolts and detent means therefor comprising two arcuate seats in each bolt spaced apart the distance of the travel of the bolts and a roller adapted to rest simultaneously in 40 either one of the seats in each bolt, a spring for holding the roller in the seats, and guards for holding the roller in operative position.

In witness whereof, I subscribe my signature, in the presence of two witnesses.

OSCAR C. RIXSON.
